SINGLE POLE-DOUBLE THROW MINIATURE VACUUM RELAY

Robert W. Hansen, San Jose, Calif., assignor to Jennings
Radio Manufacturing Corporation, San Jose, Calif., a
corporation of Delaware

Filed Apr. 19, 1965, Ser. No. 84,861

Term of patent 14 years

(Cl. D26—13)

FIG - 4

FIG - 5

FIG - 3

FIG - 2

FIG - 1

FIG. 1 is a top perspective view of a single pole-double throw miniature vacuum relay showing my new design;

FIG. 2 is an elevational view of the side opposite that of FIG. 1, on an enlarged scale;

FIG. 3 is a top plan view thereof;

FIG. 4 is a left-hand elevational view thereof; and

FIG. 5 is a right-end elevational view thereof.

I claim:

The ornamental design for a single pole-double throw miniature vacuum relay, as shown.
